BOX STAYING MACHINE

Michael J. Stumpf, Philadelphia, Pa., assignor, by
mesne assignments, to National Metal Edge
Box Company, Philadelphia, Pa., a corporation
of Pennsylvania

Application August 23, 1948; Serial No. 45,760

4 Claims. (Cl. 1—12)

1

This invention relates to an improvement in box staying machines, i. e., machines of the type adapted for the application of metal stay strips to box corners.

Machines of the type referred to here are disclosed, for example, in United States Patents Nos. 2,009,421, 1,346,573, 1,192,201 and 793,549.

Machines of the type contemplated comprise a die and anvil for the application of a stay strip to a box corner in combination with means for automatically feeding a length of stay strip to the die in each operation of the die and in which the length of stay strip is cut off and fastened to a box corner laid on the anvil.

Machines of the character contemplated here have heretofore been so constructed as to be adaptable to feed stays of a length up to a given maximum only. As a consequence, where, for example, a length of stay strip greater than the maximum length for any given machine was desired, a separate machine was required.

Now in accordance with this invention there is provided a box staying machine so constructed as to selectively feed up to normal maximum lengths of strip, or to double maximum length.

Having now indicated, in a general way, the nature and purpose of this invention, I will proceed to a detailed description of a preferred embodiment thereof with reference to the accompanying drawings, in which:

Figure 1 is a side elevation, partly broken away, of a box staying machine embodying this invention.

Figure 2 is an opposite side view, partly broken away, of the upper portion of the machine shown in Figure 1.

Figure 3 is a detail view of an element of the machine looking in the direction of the arrow Figure 1.

Figures 4—8 are detail views of an element of the machine in different positions in an operational cycle.

Figure 9 is a detail view of an element of the structure shown in Figures 4—8.

Referring now to the several figures, the machine basically is of the construction as shown, for example, in U. S. Patent No. 1,346,573, in that it comprises a frame 1, from which is supported a fixed anvil 2, with which is adapted to cooperate a reciprocating die 3. Into the die is fed a length of metal stay strip 4, from a roll 5, supported from frame 1.

As is usual, the die 3 is reciprocated by a motor 6, started and stopped by a foot pedal 9 and arranged to drive a shaft, mounted in frame

1, through gearing 8. The shaft 7 carries a crank 10, to which an end of a link 11 is connected, the other end of link 11 being connected to an end of a lever 12 fulcrumed on bell crank 14. A two armed lever 13 is pivoted on a pivot 13' to lever 12. One arm of the lever 13 is hooked for engagement with an arm of a bell crank lever 14. The bell crank 14 is connected to the die 3 by a link 15. The lever 13 will be normally held in engagement with bell crank lever 14 by spring 16; and the connection thus made will operate the die downwardly to close with the anvil. The die will be retracted through the operation of the link 15.

As a safety feature a guard 17 carried by the die 3 will be lifted, if in the descent of the die the operator's hands be in the path of the die. From the guard 17 extends a rod 18, an end of which, in lifting of the guard, will contact an arm of lever 13 and throw the lever out of engagement with bell crank 14, thus breaking the driving connection for the die, interrupting the downward movement of the die, which is then held by spring 19. Lever 13 will reengage with bell crank 14 under the influence of spring 16 in the continued rotation of shaft 7. During the upward movement of the die a length of the metal stay strip 4 will be fed to the die by means of the usual feeder device 20 actuated by shaft 7 through crank 21 and link 22, and the usual cut-off mechanism (not shown) is provided to sever the length of stay strip as it is affixed by the closing of the die with the anvil.

Now more specifically with reference to the invention contemplated here, a lever 23 is carried on the pivot 13' by which the lever 13 is connected to lever 12 and on the opposite side of lever 12 from the lever 13.

The lever 23 carries a laterally extending finger 24. Pivotally mounted on bell crank lever 14 in operative relation to lever 23 is a cam 25, from the side of which extend pins 26 and 27. A spring 28, extending from bell crank 14, overlies the cam and acts as a detent.

Mounted on frame 1 is a support 29 on which is pivotally mounted a triangular finger 30, beneath which is a top member 31 connected to the support 29 by a slot and pin connection and connected to the finger 30 by a spring 32.

The arrangement of the cam 25, lever 23 and triangular finger 30 is such that with the stop member 31 positioned as shown in Figures 4—8, the lever 23 will, in alternate downward movement of the die 3, be actuated by the cam 25 to turn lever 13 to break its connection with bell

crank lever 14, as though the safety device had been operated, with the result that the stay strip feeding mechanism will be actuated twice, with feed of a double length of stay strip for each closing of the die with the anvil. Again, the arrangement is such that by adjustment of the stop member 31 to position the triangular finger 30 as shown in Figure 9, the cam 25 will not actuate the lever 23 to break the driving connection to the die and the die will close with the anvil with normal feed of stay strip.

In more detail, with reference to Figures 4-8, where a double feed of strip is desired the stop 31 is set to position finger 30 as shown in Figure 4. With the lever 23 and cam 25 in the position shown in Figure 4, the lever 13 will be in engagement with bell crank lever 14 and on movement of lever 12 in the direction of the arrow, Figure 4, the die will be brought down into engagement with the anvil. In the course of the descent of the die, the pin 27 on cam 25 will pass to a position beneath finger 30, the finger being depressed against spring 32 in the passage of the pin 27.

When the die is in closed position, the several parts will be related as shown in Figure 5.

In the opening or upward movement of the die, during which feed of a length of strip will take place, the pin 27 on cam 25 will engage finger 30 and in continued upward movement the cam will be turned by finger 30 and held by spring 28 to the position shown in Figure 6. The pin 27, in the changed position of the cam, will pass by the end finger 30.

On completion of the opening stroke of the die, the several parts will be in the position shown in Figure 7, in which position the cam has turned the lever 23 counterclockwise, which causes turning of the lever 13 so that the hooked end thereof is retracted from engagement with bell crank lever 14, thus breaking the driving connection.

Now, when the lever 12 again moves in the direction of the arrow, Figure 7, which would normally cause the die to descend, there is no downward movement of the die due to the fact that the connection between lever 12 and bell crank lever 14, normally made by lever 13, is broken. In the continued movement of the lever 12 in the direction of the arrow, Figure 7, the finger 24 on lever 23 contacts with the pin 26 on cam 25 and effects turning of the cam back to the position shown in Figure 4. The turning of the cam permits the finger 24 to pass the pin 26 in the continued movement of the lever 12, as shown in Figure 8.

In the continued movement of lever 12, in the upward stroke thereof, a second feed of strip occurs and when the lever 12 reaches its upper position, the hooked end of lever 13 is reengaged with bell crank lever 14 under the influence of spring 16, the cam 25 offering no obstruction to the turning of the lever 23 incidental to the reengagement of lever 13 with bell crank lever 14. The parts are then in the position shown in Figure 4.

It will now be noted that with the finger 30 adjusted as shown in Figures 4-8, the die will close with the anvil on every other stroke of the lever 12, while, at the same time, feed of strip will take place on every upward stroke of the lever 12, so that double feed will occur on each closing of the die with the anvil.

When it is desired to operate with single feed of stay strip for each closing of the die and anvil, the above described mechanism is thrown out of operation by positioning triangular finger 30 out of the path of pin 27 on cam 25, by adjustment of stop 31, as shown in full lines, Figure 9.

In practical use of the mechanism as above described, for example, given a machine adapted normally to feed a length of strip up to 12 inches, where it is desired to apply a strip of 24 inches in length, a 24 inch feed of strip between closing of the die and anvil will be obtained with the above described mechanism. Half of this length will be applied in each closing of the die and anvil and the other half will be applied subsequently with the machine in normal operation without supply of strip.

While the machine in accordance with this invention has been described more particularly with reference to feed of box staying strip or for the staying of boxes, it will be understood that it is equally adaptable to the application of metal for the provision of a cutting edge, such as is provided in dispensing packages in connection with rolled paper to enable lengths to be readily drawn out and severed.

It will be appreciated that various modifications in detail may be made in the above described mechanism without departing from this invention as defined in the appended claims.

What I claim and desire to protect by Letters Patent is:

1. In a machine for applying metal strip, a die 35 and anvil, a prime mover, a breakable driving connection between the prime mover and the die for closing the die with the anvil, means for feeding a length of metal strip to the die in its opening movement and means for breaking the driving connection to the die in alternate opening movements of the die.

2. In a box machine, a die and anvil, a prime 45 mover, a breakable driving connection between the prime mover and the die for closing the die with the anvil, means for feeding a length of metal strip to the die in the opening movement of the die and cam means actuated in the opening movement of the die for breaking the driving connection to the die in alternate opening movements of the die.

3. In a machine for applying metal strip, a die 55 and anvil, a prime mover, a driving connection including a latch between the prime mover and the die for closing the die with the anvil, means for feeding a length of metal strip to the die in the opening movement of the die and cam means for opening the latch in alternate opening movements of the die.

4. In a machine for applying metal strip, a die 60 and anvil, a prime mover, a breakable driving connection between the prime mover and the die for closing the die with the anvil, means for feeding a length of metal strip to the die in the opening movement of the die, cam means actuated in the opening movement of the die for breaking the driving connection to the die in alternate opening movements of the die and means for rendering said cam means inoperable.

MICHAEL J. STUMPF.
